(57) **CLAIM**

The ornamental design for a 3D printer test bench model as shown and described.

DESCRIPTION

FIG. 1 is an front perspective view of a 3D printer test bench model, showing the new design;

FIG. 2 is a rear perspective view of the design of FIG. 1;

FIG. 3 is a front side view of the design of FIG. 1;

FIG. 4 is a rear side view of the design of FIG. 1;

FIG. 5 is a right side view of the design of FIG. 1;

FIG. 6 is a left side view of the design of FIG. 1;

FIG. 7 is a top side view of the design of FIG. 1; and,

FIG. 8 is a bottom side view of the design of FIG. 1.

1 Claim, 5 Drawing Sheets

FIG. 1

FIG. 2

FIG. 3**FIG. 4**

FIG. 7**FIG. 8**
